COMBINED BEVERAGE AND FOOD VENDING BUILDING

Herbert J. Oyler, 202 S. Montreal, Dallas, Tex.

Filed July 27, 1959, Ser. No. 56,938

Term of patent 14 years

(Cl. D13—1)

Fig. I

Fig. II

Fig. III

Fig. IV

Fig. V

Fig. VI

FIG. I is a front elevational view of a combined beverage and food vending building showing my new design;

FIG. II is a rear elevational view of a combined beverage and food vending building;

FIG. III is a side elevational view of a combined beverage and food vending building taken from the right side of FIG. I;

FIG. IV is a side elevational view of a combined beverage and food vending building taken from the left side of FIG. I;

FIG. V is a top plan view of a combined beverage and food vending building; and

FIG. VI is an enlarged fragmentary, elevational view of a portion of the front of a combined beverage and food vending building.

I claim:

The ornamental design for a combined beverage and food vending building substantially as shown.
